Primary Examiner — R. Johnson(74) *Attorney, Agent, or Firm* — Westman, Champlin & Koehler, P.A.(57) **CLAIM**

The ornamental design for a pedal, as shown and described.

DESCRIPTION

FIG. 1 is a top, rear perspective view of a pedal; FIG. 2 is front elevation view thereof; FIG. 3 is a rear elevational view thereof; FIG. 4 is a left side elevational view thereof; FIG. 5 is a right side elevational view thereof; and, FIG. 6 is a top plan view thereof.
The bottom of the pedal has unornamented surfaces.
Portions of the pedal shown in broken lines are for illustrative purposes only and form no part of the claimed design.
